[57] CLAIM

The ornamental design for a towel warmer, as shown and described.

DESCRIPTION

FIG. 1 is a front elevational view of a towel warmer showing my new design;

FIG. 2 is a rear elevational view thereof;

FIG. 3 is a right side elevational view thereof, the left side being a mirror image of that shown;

FIG. 4 is a top plan view thereof;

FIG. 5 is a bottom plan view thereof;

FIG. 6 is a top, front, and right side perspective view of a second embodiment thereof, the only difference residing in the appearance of the insert panels on the front elevation;

FIG. 7 is a front elevational view of a third embodiment thereof;

FIG. 8 is a rear elevational view of the third embodiment;

FIG. 9 is a right side elevational view of the third embodiment, the left side being a mirror image of that shown;

FIG. 10 is a top plan view of the third embodiment;

FIG. 11 is a bottom plan view of the third embodiment; and,

FIG. 12 is a top, front, and right side perspective view of a fourth embodiment thereof, the only difference from the third embodiment residing in the appearance of the insert panels on the front elevation.
